UNITED STATES PATENT OFFICE.

JAMES EDWARD LEA, OF MANCHESTER, ENGLAND.

FUEL-FEED INDICATOR.

Application filed April 25, 1922, Serial No. 556,555, and in Great Britain September 10, 1921.

This invention has reference to apparatus primarily for use with mechanical stokers of the endless chain grate type, and also for use with other and like appliances adapted 5 to feed or convey granular substances through an orifice, and the object of the invention is to provide improved means, in combination with the said type of mechanical stokers or appliances, whereby the "rate 10 of feed" of the fuel into the boiler furnace, or that of the granular material through the orifice at any moment will be instantly indicated, thereby in the case of fuel fed into a furnace indicating the rate at which the 15 fuel is being consumed, which will afford useful data by which to check the steam raising qualities of the fuel or boiler, and in the case of other materials, furnish useful data as to the rates at which the materials are 20 dealt with, say in being discharged into or from a vessel, or otherwise disposed of.

Endless chain grate stokers for boiler furnaces are usually provided with change speed gear by which the grate may be run at 25 several different speeds (usually four) to suit the rate at which it is desired to feed the fuel into the furnace, and the total quantity of fuel that enters the furnace varies 30 with the speed of the grate and the thickness of the layer of fuel, therefore, for each speed, the quantity of fuel delivered is proportional to the thickness of the layer of fuel, and for any given thickness the 35 quantity of fuel delivered is proportional to the speed of the grate.

The present invention takes advantage of these facts and consists essentially of an instrument or apparatus wherein is an element provided with as many scales as there 40 are separate speeds for the endless grate or other conveyor to run at, and wherein is another element moveable over any one of said scales with any change in the thickness 45 of the layer of fuel or other material to be measured, both of the elements being automatically operated, or one being automatically operated and the other being operated or set by hand, or both being set by hand. Each scale is calibrated to indicate the rates 50 of feed for a particular speed in relation to various thicknesses in the layer of material, and said calibration will usually be expressed in cubic feet, or pounds. Each scale may also be calibrated to denote in

inches various thickness in the layer of material. 55

Upon the accompanying drawings:

Fig. 1 illustrates an end elevation, and

Fig. 2 a front elevation of a chain grate stoker, with one example of the invention 60 applied thereto.

Figs. 3 and 4 illustrate further end elevations of chain grate stokers with two further examples of the invention applied thereto. 65

Fig. 5 illustrates a sectional plan, and

Fig. 6 a cross sectional elevation of a further example of the invention.

Figs. 7 and 8 illustrate sectional elevations of the improved appliance as applied 70 to the coal meter forming the subject of my prior Patent No. 1,293,130.

Fig. 9 is an exterior view of the indicator shown in Figs. 5 and 6.

Fig. 10 is a perspective view of the indicator shown in Fig. 8, but showing the same attached to the coal meter forming the subject of my prior Patent No. 1,293,130. 75

Fig. 11 is a perspective view of a number of chain grate stokers each fitted with the 80 construction of indicator shown in Figs. 5, 6 and 9.

Fig. 12 illustrates in diagram a side sectional elevation of a conveyor, a hopper with orifice, a regulator controlling the orifice, and speed-change mechanism for the conveyor, with one example of the invention applied thereto. 85

Referring to Figs. 1 and 2, a disc *a* is employed, said disc being keyed to the spindle *a'* by which the speed gears of the grate (not shown) are changed, and such disc, on one of its side faces, is marked with a series of scales *b*, one for each of the different speeds of the furnace grate, see Fig. 2. 90

Movable across one half of the face of the disc is a pointer *c*, which in one direction may be moved by a spring *d* anchored to a ring *e* lying around said gear-changing spindle, and in the opposite direction may be moved by the door of the boiler furnace or the means, rack *f*, used for raising and lowering such door. 95

With each adjustment of the spindle to change the speed of the grate from one speed to another, the disc *a* is rotated so as to bring the scale related to such speed behind the pointer *c*, which at once indicates on the scale 100 105

the rate of feed of the fuel for the particular speed of grate and thickness of layer of fuel. With any adjustment of the furnace door, the pointer *e* is moved across the face of the disc 5 *a* and is thereby automatically set to the correct position for indicating the rate of feed at any moment for the then thickness of the layer of fuel and velocity of grate.

In another example of the invention, see 10 Fig. 3, a flat plate *g* is employed, marked with the several scales aforesaid, which are arranged parallel with each other, and such plate is adapted to slide to and fro in a direction at right angles to the scales marked 15 thereon, and take up different positions under the action of the speed-changing mechanism and a counter-balance weight *g'*. Mov- 20 able across the said plate in a direction parallel with the scales *g* is a "pointer" *h* connected directly (or indirectly) to the furnace door or its operating means.

With a change of speed of grate, the said plate *g* is moved endwise, thereby bringing the scale related to the particular speed be- 25 hind the pointer *h*, whilst with a change in the thickness of the layer of fuel the pointer is moved along the scale, the position of the pointer indicating the then rate of feed.

In Fig. 4 the plate *g* is shown fixed, and 30 the pointer *h*, which is connected to the door-operating member, is made to a width which allows it to extend across the several scales. In this case, it is necessary first to ascertain the speed of the grate, and therefore the par- 35 ticular scale for such speed in order to determine the rate of feed.

In lieu of a flat plate, a rotatable cylinder *i* may be employed, see Figs. 5 and 6, marked with the scales and the pointer *j* may be carried 40 on an adjacent and parallel spindle *k* movable endwise, the cylinder being rotated by the gear-changing mechanism or by hand and the pointer being moved by the furnace door or door-operating mechanism. To pre- 45 vent the pointer *j* touching the cylinder *i* the arm *j'* carrying same may be slidably supported upon a fixed guide rod *l*.

Another example of the invention which 50 can be conveniently combined with the fuel meter forming the subject of my prior Patent No. 1,293,130 consists of a pointer *m* mounted on an extension *n* of the spindle or bar carrying the endwise moving pinion of the said meter and of a cylinder *o* surround- 55 ing said pointer, such cylinder being closed at one end and open at the other, and at such open end, being journaled in a bearing ring *p* secured to the end of the outer casing of the instrument. In such cylinder are slots *q* one for each speed of the grate, and alongside each slot, the outer face of the cylinder is marked with one of the said scales. In 60 this arrangement the element which carries the scales is adjusted by hand, the cylinder being provided with a knurled rim to facili- 65

tate the rotation. The pointer *m* is moved automatically by the said pinion spindle of the meter, the position of the pointer, which is to be seen through the slot in the cylinder, indicating, in conjunction with the scale, the rate of feed at any moment. The cylinder *o* might also be automatically adjusted by a connection with the gear changing mechanism.

In Fig. 8, the cylinder *o* is made a fixture 75 and has only one slot, while inside the cylinder is a drum *r*, carrying the scales, and rotatable by hand (or by the speed changing mechanism), a pointer *s* carried by the extension *n* moving along the scale which for 80 the time comes opposite the slot in the cylinder *o*.

As shown in Fig. 12, the hopper 13 has an orifice 14 for the delivery of the material 15 on a conveyor 16. The conveyor is driven by chain 17 from a change speed gear box 18 having a change speed control wheel 19. Over the orifice is a regulator 20. Mounted adjacent to the hopper is an indicator to show the rate of feed and comprises a drum 21 having a series of scales 22, three of which are visible in the drawing. The drum is mechanically connected by a cable 23, passing over pulleys 24, to the control wheel 19 so as to turn simultaneously therewith to present at all times the scale which corresponds to the selected gear ratio, which selection is determined by the control wheel 19. A pointer 25 is slidably mounted adjacent to the selected scale 22, so as to move over same and is coupled by a cable 26 to the regulator 20 so as to assume a position relative on the scale to the size of the orifice as determined by the position of the regulator. Incorporated with the apparatus is an integrator unit comprising a toothed drum 27 geared to the conveyor, with which a sliding intermediate pinion 28 engages, carried by the pointer 25, so as to obtain on the counter 29 a reading proportional to the volume of the material delivered.

Whilst preferring to adjust one or both of the indicating elements automatically, both may be adjusted by hand, that is to say, with the speed of the grate and thickness of layer of fuel known, the rate of feed can be readily determined by bringing the scale for the known speed behind the "pointer" previously arranged, according to the known thickness of fuel along the scale.

Although chiefly for use with mechanical stokers of the endless chain grate type, it will be understood that the invention may be usefully employed with other apparatus employing an endless conveyor for feeding granular materials through an orifice.

The invention may also be used with apparatus in which only the speed of the conveyor varies, and the thickness of the layer of material remains constant. In such case

the pointer will be stationary, and the indicator only adjusted. Obviously, when the speed of the conveyor is constant, and only the thickness of the layer of granular material varies, one scale only will be necessary, or the indicator will not require to be adjusted after once being set for a particular speed.

What I claim is:—

- 10 1. In apparatus comprising a hopper having an orifice through which granular material is to be delivered, a conveyor extending through said orifice, means for driving the conveyor at one or other of several speeds, and a regulator controlling said orifice, in combination a rotary indicator having a series of scales, one for each speed of the conveyor and each scale calibrated to indicate the rate of feed for a particular speed 20 in relation to various thicknesses in the layer of granular material, a pointer movable over the scales to positions corresponding to the thickness of the layer of material when passing through the orifice, means for 25 operably connecting the pointer to the orifice regulator, and further means for oper-

ably connecting the indicator to the change-speed control mechanism of the conveyor, as set forth.

2. In apparatus comprising a hopper having an orifice through which granular material is to be delivered, a conveyor extending through said orifice, means for driving the conveyor at one or other of several speeds, and a regulator controlling said orifice, in combination an indicator having a series of scales, one for each speed of the conveyor, and each scale calibrated to indicate the rates of feed for a particular speed in relation to a particular thickness of the layer of granular material passing through the orifice, a pointer for said indicator coming opposite the calibrations of the scales corresponding to the rates of feed for each speed of the conveyor, and means actuated by the speed changing mechanism of the conveyor to bring the correct scale calibration to come in the indicating position with relation to the pointer, as set forth.

In testimony whereof I have signed my name to this specification.

JAMES EDWARD LEA.
